UNITED STATES PATENT OFFICE.

WILLIAM ROACH, OF HOWARD, SOUTH DAKOTA.

RAILROAD-TRACK-MOWING MACHINE.

1,184,877.

Specification of Letters Patent. Patented May 30, 1916.

Application filed January 12, 1915. Serial No. 1,830.

To all whom it may concern:

Be it known that I, WILLIAM ROACH, a citizen of the United States, residing at Howard, in the county of Miner and State 5 of South Dakota, have invented a new and useful Railroad-Track-Mowing Machine, of which the following is a specification.

The device forming the subject matter of this application is a mowing mechanism 10 adapted to be assembled with a hand car, the construction being such that a swath may be cut upon each side of the hand car as the latter progresses along the track. Two 15 duplicate cutting mechanisms are provided, the same being disposed upon opposite sides of the hand car. These cutting mechanisms may be raised individually and may be swung individually, in a forward and rearward direction, horizontally. A prime 20 mover is mounted upon the hand car and is operatively connected with certain of the wheels thereof for the purpose of driving the car. This prime mover, further, is operatively connected with both of the cutting 25 mechanisms, to actuate the same. At the will of the operator, the cutting mechanisms may be detached from the prime mover so that the latter may drive the car independently of the cutting mechanisms.

30 The present invention aims to improve a track mowing mechanism along the lines above indicated, and to provide novel structural features which will be set forth more clearly hereinafter.

35 With the above and other objects in view which will appear as the description proceeds, the invention resides in the combination and arrangement of parts and in the details of construction hereinafter described 40 and claimed, it being understood that changes in the precise embodiment of the invention herein disclosed, can be made within the scope of what is claimed, without departing from the spirit of the invention.

45 In the accompanying drawings:—Figure 1 shows the invention in top plan; Fig. 2 is a front elevation, the cutter bar at one side of the car being raised up and the other 50 cutter bar being lowered; and Fig. 3 is a perspective depicting the cutter supporting arm and attendant parts.

55 In the drawings, there is shown a car embodying a platform 1 and axles 2 carrying wheels 3 adapted to traverse tracks 4. Mounted upon the platform 1 of the car is

an engine 5 the crank shaft of which is denoted by the numeral 6, the crank shaft 6 carrying a pulley 7 about which is trained a belt 8, the belt being engaged with a pulley 60 9 carried by the shaft 10 supported as shown at 11 upon the framework of the car. Attached to one end of the shaft 10 is a beveled gear wheel 12 meshing with a beveled pinion 14 on one of the axles 2. The foregoing arrangement of parts provides a mechanism whereby the car may be propelled along the track 4 through the instrumentality of the engine 5.

Interposed in the engine shaft 6 is a 70 clutch 15 of any desired sort whereby, at the will of an operator, a pair of duplicate cutting mechanisms may be coupled up with the shaft 6 and be disconnected therefrom, to the end that the car may be moved along 75 the track without actuating the cutting means. Carried by the forward end of the crank shaft 6 is a crank disk 16 to which oppositely extending pitmen 17 are eccentrically connected. As shown to best ad- 80 vantage in Fig. 3, each pitman 17 may be a longitudinally adjustable structure, comprising telescoped parts 17^a and 17^b, united by a cotter pin or the like, shown at 17^c. The pitmen 17, respectively, form parts of 85 duplicate cutting mechanisms located upon opposite sides of the car, and since these cutting mechanisms are alike, but one of them need be described in detail.

Pivotedly supported as shown at 18 upon 90 the framework of the car, to swing both vertically and horizontally is an arm 19. Secured to the arm 19, as shown best in Fig. 3 is a bracket 20. A retractile spring 21 is provided, the forward end of the spring 21 95 being connected to one of a pair of guards 29 mounted on a support 28 pivoted as shown at 27 to a head 22 which is attached to the outer end of the arm 19, the construction being such that the support 28 is mounted 100 to swing in a vertical direction. The rear end of the retractile spring 21 is attached, as shown in Fig. 1, to the framework of the car. Loosely united with the head 22 is a connection in the form of a rod 23, the same 105 being pivoted to a lever 24 fulcrumed upon the car and carrying a latch mechanism 25 adapted to coöperate with a segment 26 upon the car. The head 28 carries a finger bar 30, upon which a cutter bar 31 is mounted to 110 reciprocate.

It will now be understood that by ma-

nipulating the lever 24, the finger bar 30, together with the support 28, the head 22 and the rod or arm 19, may be swung in a horizontal direction, the parts pivoting at 5 the point 18. The spring 21 serves to hold the finger bar 30 and attendant parts against swinging movement in a horizontal direction, saving when actuated by the lever 24 and attendant mechanisms.

10 A means is provided for reciprocating the cutter bar 31 upon the finger bar 30, and with this end in view, a link 32 is pivoted to the inner end of the cutter bar, the link 32 being pivoted to a link 33 which in its 15 turn, is pivoted to a lever 34, fulcrumed as shown at 34^a upon the bracket 20. The lever 34 is a composite structure and comprises, as shown in Fig. 3, telescoped parts 35 and 36, held in adjusted relation with respect 20 to each other by means of a cotter pin 37 or the like. The upper end of the lever 34 is pivoted as shown at 38 to the outer end of the pitman 17.

25 The effective length of the lever 34 may be altered by telescoping the parts 35 and 36 with respect to each other. Thus the power arm of the lever may be lengthened or shortened at will, the telescoping feature being of use, further, under some circumstances, when it is desired to raise and lower the arm 19 or the cutter bar 31, as will be described hereinafter.

30 An upwardly extended spring 39 is secured at its outer lower end to the bracket 35 20, the upper end of the spring 39 being attached to a bracket 40 on the platform 1 of the car. This spring 39 serves to support, partially, the weight of the cutting mechanism and to render the raising thereof comparatively easy.

40 A chain 41 is attached to one of the guards 29 and is connected with a crank arm 42 formed upon one end of a shaft 43 journaled in bearings 44 on the frame of 45 the car. Connected with the shaft 43 is a lever 45 having latch mechanism 46 adapted to coact with a segment 47 on the car.

50 It will now be understood that by manipulating the lever 45, the finger bar 30 and the cutter bar 31 may be swung upwardly, as shown at the left hand side of Fig. 2, with the point 27 as a pivot. This operation takes place, ordinarily, when it is desired to use the cutting mechanism no 55 longer. It is possible, further, to raise the arm 19 and the cutter bar 31 when the parts are in the operative, cutting positions shown at the right hand side of Fig. 2. To accomplish this result, a chain 48 is attached to 60 the bracket 20, the upper end of the chain

48 being attached to a crank arm 49 formed on a shaft 50 journaled in suitable bearings 50^a on the car, the shaft 50 carrying a lever 51 provided with latch mechanism 52 adapted to coöperate with a car supported segment 53.

65 The operation of the device has been dealt with hereinbefore, step by step, but briefly considered is as follows:—The car is propelled by a driving mechanism comprising 70 the engine 5, the belt 8, the shaft 10, the beveled pinions 12 and 14 and one of the axles 2. Each cutting mechanism is actuated from the engine 5 through a gear train comprising the pitman 17, lever 34, links 33 75 and 32, and the cutter bar 31. By manipulating the clutch 15, the cutting mechanism may be thrown out of gear and the car may be propelled without actuating the cutting mechanism. Each of the cutting mechanisms may be swung in a vertical plane by manipulating the lever 24 which in its turn, swings the cutter bar 31 and the arm 19. The arm 19 and the cutter bar 31 may be raised together through the medium of the 80 chain 48, the shaft 43 and the lever 45. The cutter bar 31 may be raised and lowered independently of the arm 19 through the medium of the chain 41, shaft 50 and lever 51.

90 Having thus described the invention, what is claimed is:—

1. In a device of the class described, a vehicle; an arm connected with the vehicle to swing both horizontally with respect to 95 the vehicle and vertically; a cutter bar connected with the arm to swing vertically; means for swinging the arm vertically; means for swinging the arm horizontally; and means for swinging the cutter bar vertically upon the arm independently of the 100 arm.

2. In a device of the class described, a vehicle; an arm pivoted to the vehicle and mounted to swing horizontally; means connected with the arm for swinging the arm horizontally in one direction with respect to the vehicle; spring means for resisting the horizontal swinging movement of the arm in said direction with respect to the 110 vehicle; and a cutter bar carried by the outer end of the arm.

In testimony that I claim the foregoing as my own, I have hereto affixed my signature in the presence of two witnesses.

WILLIAM ROACH.
